UNITED STATES PATENT OFFICE

LEW A. HURLBURT, OF PERRY, IOWA

READING EASEL

Application filed May 5, 1928. Serial No. 275,528.

The object of my invention is to provide a reading easel of simple, durable and comparatively inexpensive construction.

A further object of my invention is to provide an easel especially adapted to support a magazine or book in reading position either on a desk or table or on the legs of a user.

More particularly it is my object to provide an easel of this character in which a support is provided for holding a magazine or the like in open position with an adjustable leg member on the under surface of the easel so that this leg member can hold the supporting member in an inclined position relative to a table top.

Still a further object is to provide the leg member with a pair of U-shaped portions adapted to engage the legs of a user so that the magazine will be supported in easy reading position with respect to the user when in use.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is a perspective view of my device illustrating it in use on a table top and indicating in dotted lines a magazine open thereon.

Figure 2 is a similar perspective view, viewing the device from the under surface thereof.

Figure 3 is an enlarged sectional view on the line 3—3 of Figure 1.

Figure 4 is a sectional view on the line 4—4 of Figure 3.

Figures 5 and 6 are side elevations of the device showing it in two different positions of adjustment; and

Figure 7 is a side elevation partially in section to illustrate the device when folded up.

In the accompanying drawings I have used the reference numeral 10 to indicate a support. This support may be made of sheet metal or other desirable material and for rein-

forcement purposes, the edges thereof are bent downwardly to form flanges 12. The lower end of the support 10 terminates in an upwardly hooked portion 14 for the purpose of engaging the lower edge of a magazine 16 or the like, positioned on the support.

Secured to the undersurface of the support 10, is a pair of bars 18 having foot portions 20 secured to the support 10 by riveting or spotwelding. The bars 18 are similar and have curved portions 22 at one of their ends and notches 24 formed at their opposite ends.

A leg member A consisting of a pair of side arms 26 and connecting portions 28, is adjustably mounted on the bars 18. The side arms 26 are bent outwardly as indicated at 30 and then downwardly as at 32 for partially surrounding the bars 18. Rivets 34 then extend through the arms 26 and through the portions 32 whereby an encircling loop is provided on the free end of each arm 26. These loops as clearly illustrated in Figure 4, encircle the bars 18. It may here be mentioned that the distance between the portion 30 and the rivet 34 is a little greater than the width of the bar 18.

The portions 28 of the leg member A are U-shaped as clearly shown on the drawings and where these portions connect together and where they connect with the side arms 26, rubber sleeves 36 are positioned on them. These sleeves are provided to prevent marring a table top when the device is positioned thereon.

Practical operation

In the operation of my device, the leg member A normally assumes the position indicated at B by dotted lines in Figure 3 and by full lines in Figure 7. In this position the device is compactly folded into a small space so that it can be conveniently carried in a suitcase. It can also be hung on a wall by positioning the opening 38 in the upper end of the support 10, over a nail or hook.

When it is desired to use my device, the leg member A may be moved from the position B by swinging it as indicated by the arrow 40. In doing this the encircling loops formed by the arms 26, the portions 30 and

32 and the rivets 34, merely travel around the curved portion 22 of the bars 18 similar to swinging on a pivot. The member A may then be moved to the full line position illustrated in Figure 3 whereby the rivets 34 engage the notches 24 for supporting the device in slightly inclined position relative to a table top 42.

If it is desirable to increase the inclination 10 of the support 10 with respect to the table top 42 as shown in Figures 5 and 6, the leg member A may be moved to the positions C and D respectively. When moving to these positions, it will be obvious that the encircling upper ends of the arms 26 may remain in the same position longitudinally, with respect to the bars 18 but the leg member A may be swung in either of the positions due to the loose connection provided by the space 20 between the portions 30 and the rivets 34 being greater than the widths of the bars 18.

Other positions may also be had by adjusting the leg member A longitudinally on the bars 18. In addition to using my device in connection with a table top, it may also be used on the lap of a person by placing the U-shaped portions 28 over his legs just above the knees and resting the curved portion 14 of the support 10 against his stomach. This 30 supports the magazine 16 in an easy reading position and I find that it helps considerably when reading for any length of time from a heavy magazine or book. The use of the device, furthermore, does not interfere with 35 the user crossing his legs as only one of the portions 28 need be utilized for holding the support 10 in the proper position while the user's legs are crossed.

In this case, of course, the leg member A 40 would engage the upper leg of the user. When he desires to change the crossing of his legs, he can at the same time, without inconvenience, transfer the leg member A to the other of his own legs.

45 I have found my device particularly valuable to traveling salesmen since it can be conveniently folded and carried in their suit cases and can be used by them as a writing table when they are on the train or even when in 50 an automobile. My easel when positioned as above described, is convenient to the user for writing letters, etc., thereon.

55 My device can be made very cheaply and therefore, is desirable as an advertising novelty. Both the front and the back of it, may be printed with an advertisement which will be called to the attention of the user each time he uses the device. The advertisement on the front may be of a pictorial character so that 60 it is desirable to have the device when not in use, hanging on the wall similar to a picture. This can be done as indicated in Figure 3 with the leg member A arranged at the angle shown in full lines. In this position the connecting portion between the two U-shaped

portions 28, may be hung over a nail or hook in the wall.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

75 I claim as my invention:—

1. A reading easel comprising a support, a bar on the underside thereof and a leg member mounted for sliding adjustment on said bar, said leg member being formed with a 80 comparatively deep U-shaped portion to engage the leg of a user of the easel and to be retained against side movement relative to, and consequent displacement from, the user's leg.

85 2. In a device of the class described, a support, a pair of bars on the underside thereof, a leg member having loop portions surrounding said bars and capable of longitudinal movement thereon for providing a reading easel adjustable as to inclination, said loop portions being arranged to bind on said bars when a predetermined amount of pivotal movement is imparted to the leg member.

90 3. In a device of the class described, a support, a pair of bars on the underside thereof, a leg member having loop portions surrounding said bars adapted to bind thereon when the leg member is pivoted a predetermined degree relative to said bars and capable of longitudinal movement thereon for providing a reading easel adjustable as to inclination, said bars having curved portions at their 95 ends for allowing said leg member to be folded against said support.

95 4. In a device of the class described, a support, a pair of bars on the underside thereof, a leg member having loop portions surrounding said bars adapted to bind thereon when the leg member is pivoted a predetermined degree relative to said bars and capable of longitudinal movement thereon for providing a reading easel adjustable as to inclination, said bars having notched portions for 100 said leg member to enter when in one position of its movement.

105 5. In a device of the class described, a support, a pair of bars on the underside thereof, a leg member having loop portions surrounding said bars adapted to bindingly coat 110 therewith and capable of longitudinal movement thereon for providing a reading easel adjustable as to inclination, said leg member having a pair of U-shaped portions adapted to engage the legs of a user when he is sitting 115 in reading position.

120 Des Moines, Iowa, April 19, 1928.
